UNITED STATES PATENT OFFICE.

RICHARD C. ROSE, OF OSCEOLA, ARKANSAS.

CONDENSER.

Application filed October 27, 1926. Serial No. 144,527.

This invention relates to fixed condensers employed in radio hook-ups, and aims to provide novel means whereby the clips at the ends of the condensers may be rigidly secured in position.

Another object of the invention is to provide a condenser wherein the clips are made of a plurality of sections, means being provided whereby the condensers may be secured to a supporting structure.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a plan view of a condenser constructed in accordance with the invention.

Figure 2 is a sectional view taken on line 2—2 of Figure 1.

Figure 3 is a perspective view showing the sections of a condenser clip as disconnected.

Figure 4 is a fragmental bottom plan view of the condenser.

Figure 5 is a section on the line 5—5 of Figure 4.

Referring to the drawing in detail, the condenser embodies a pair of glass members 5 and 6 respectively, which are preferably rectangular in formation, the same being separated by means of the insulating material 7.

Plates 8 and 9 respectively are arranged on opposite sides of the insulating material and contact with the upper and lower glass members 5 and 6 as clearly shown by Figure 2 of the drawing.

As illustrated the plates 8 and 9 are formed preferably of heavy tin foil and as shown, extend downwardly and inwardly underlying the glass member 6, the inwardly extended portions being formed with openings registering with openings formed in the glass members and disposed adjacent to the ends thereof.

These registering openings accommodate

the rivets 10 whereby the several elements of the condenser are held assembled.

At each end of the condenser, is a clip 55 embodying a main or body portion 11, a cooperating member 12 and a securing plate 13, which are formed of spring metal so that they will exert a tension on the members 5 and 6, to grip them securely. These 60 members are provided with openings registering with the first mentioned openings so that the rivets may also pass therethrough and secure them to the glass members.

Forming a part of each clip is a tongue 14 65 that extends laterally from the body portion of the clip and upwardly, where it passes through the elongated opening 15 of the cooperating member 12 to secure them together, the offset portion 16 of the tongue resting 70 over the outer edge of the member 12 associated therewith to hold the member 12 into close engagement with the upper glass member 5.

Openings 17 are formed in the members 75 11, for the reception of solder employed as a medium for securing the plates 9 to the member 11.

The upper and lower edges of the openings of the condenser are countersunk as so clearly shown by Figure 2, so that pressure exerted on the ends of the rivets to secure them in position, will not break the glass members.

It might be further stated that the plates 85 13 are formed with openings to accommodate securing screws whereby the device may be secured to a supporting structure.

I claim:

1. A condenser including a body portion 90 formed of spaced insulating members having openings extending therethrough, a clip at each end of the body portion, said clip embodying an upwardly extended tongue formed with a shoulder at its base, a co-95 operating member having an elongated opening to receive the tongue, said shoulder adapted to engage the cooperating member to hold it in position, and a securing plate secured to the bottom of the condenser. 100

2. A condenser including a body portion formed of spaced insulating members, a clip at each end of the body portion, said clip including a main portion having one of its

ends extended under the body portion and having an upstanding tongue, a member having an elongated opening and positioned on the upper surface of the body portion, 5 said tongue adapted to pass through the clip opening, means extending through the clip and body portion to secure the clip into po-

sition, and a securing plate secured to the under side of the body portion and extended beyond the ends thereof. 10

In testimony that I claim the foregoing as my own, I have hereto affixed my signature.

RICHARD C. ROSE.
